Monarch Company, St. Louis, Mo., a corporation of Missouri

Application July 29, 1937, Serial No. 70,725

Term of patent 7 years

To all whom it may concern:

Be it known that I, David Chapman, a citizen of the United States and a resident of Chicago, in the county of Cook and State of Illinois, have invented a new, original, and ornamental Design for a Combined Waffle Iron and Tray or Similar Article, of which the following is a specification, reference being had to the accompanying drawing, forming part thereof.

waffle iron and tray or similar article showing my new design.

Figure 2 is a top plan view thereof; and
Figure 3 is a front elevational view thereof.
I claim:

The ornamental design for a combined waffle iron and tray or similar article substantially as shown,

DAVID CHAPMAN.
